BY
Thomas D. Denney
ATTORNEY.

UNITED STATES PATENT OFFICE.

RALPH B. LONG, OF FLINT, MICHIGAN.

FOLDING STOOL.

Application filed September 4, 1926. Serial No. 133,584.

My invention relates to a new and useful improvement in a folding stool and has for its object the provision of a stool having supporting legs and seat supporting arms 5 foldable in parallel relation to each other for packing to a small space and adapted for extending angularly outwardly in opposite directions from a central supporting member when in operative position.

Another object of the invention is the provision in a stool of this class of a flexible seat forming member swingably mounted on a supporting arm and adapted for folding around the supporting arms and supporting legs when in collapsed form so as to provide a covering for the same.

Another object of the invention is the provision of a folding stool of this class of a supporting member having engagement 20 members mounted thereon for limiting the pivotal movement of the supporting arms relatively thereto in one direction and so constructed and arranged as to limit the pivotal movement of the legs so as to limit their 25 spreading relatively to their supporting member.

Another object of the invention is the provision of a flexible seat forming member having a rigid rib at one side hingedly connected to a supporting arm to retain the 30 flexible seat forming member in distended position.

Other objects will appear hereinafter.

The invention consists in the combination 35 and arrangement of parts hereinafter described and claimed.

The invention will be best understood by a reference to the accompanying drawings which form a part of this specification and 40 in which,

Fig. 1 is a perspective view of the invention.

Fig. 2 is a side elevational view showing 45 a part broken away in partially collapsed form.

Fig. 3 is a side elevational view of the invention in collapsed form.

Fig. 4 is a perspective view of the central supporting member used in the invention.

As shown in the drawings the invention 50 comprises a flexible seat forming member 7 having its edges doubled over to provide sleeves 8 in which is extended a suitable reinforcing member 9, such as a chain, cable, or 55 the like, this chain or cable being exposed at

the corners and carrying securing rings 10 and 11. A supporting block is provided having the arms 12, 13 and 14 which meet at a common center and project outwardly therefrom at angles to each other. Projecting outwardly from the arms 12, 13, and 14 at their inner ends and at the upper surface thereof are flanges 15.

In the form shown I have provided three supporting arms 16, 17 and 18, each of which 65 is pivotally connected to the supporting arms 14, 12 and 13 respectively, a suitable bolt being projected through the lower ends of the arms 16, 17 and 18, and through the respective arms 12, 13 and 14. 70

As shown in Fig. 2 these supporting arms 16, 17 and 18 are adapted for folding into parallel relation with each other. Pivotally mounted on the same bolt and on each of the arms 12, 13 and 14, at the opposite side 75 thereof, are supporting legs 19, 20 and 21. As shown in Fig. 2 these legs are adapted also for folding into parallel relation with the supporting arms 16, 17 and 18. These legs as clearly appears from Fig. 4 are so 80 mounted on the arms 12, 13 and 14 that their ends engage against the inner ends of adjacent arms to limit their spreading when moved to operative position.

It will be noted that the arm 18 is of less 85 length than the arms 16 and 17. Hingedly mounted intermediate its ends on the free end of the arm 18 is a rigid brace or reinforcing member 22, which is secured to the flexible seat forming member 7 so as to retain the seat forming member in outwardly 90 spread position. The brace 22 is adapted, when moved to inoperative position, for lying in engagement with the arm 18, the arm 18 and one-half of the arm of the brace 22 95 extending a distance equal to the length of the arms 16 and 17, so that when folded in compact position the end of the brace 22 will lie flush with the free end of the arms 16 and 17. Each of the arms 16 and 17 is provided on its free end with an axially extending slot 23, a finger 24, extending upwardly from the slot 23 and the rings 10 and 11, engaging in the slots 23, these rings when engaged in this slot serving to retain the flexible seat 100 forming member in tautly stretched condition. This fabric serves to retain the arms 16, 17 and 18 in engagement with the flanges 15, so that when the stool is in operative 105 position and in use, pivotal movement of 110

the arms 16, 17 and 18 is prevented. The weight of the person seated on the seat forming member 7 will be directed almost entirely axially of the arms 16, 17 and 18 longitudinally thereof. The rings 10 and 11 5 may be disengaged from the slots 23 when desired and the arms 16, 17 and 18 and the legs 19, 20 and 21 folded into parallel relation, the flexible seat forming member serving as a member for wrapping together the 10 arms and legs into the compact form shown in Fig. 3.

It is believed that the utility of such a device is evident as it may be folded into sufficiently small form to be carried easily in 15 one's pocket and used when necessary. The limiting means used for limiting the pivotal movement of the legs and arms is one which is quite simple and effective for the purpose, while at the same time permitting economical 20 manufacture.

While I have illustrated and described the preferred form of my invention, I do not 25 wish to limit myself to the precise form of structure shown, but desire to avail myself of such variations and modifications as may

come within the scope of the appended claim.

Having thus described my invention what I claim as new and desire to secure by Letters Patent is:

In a stool of the class described, a supporting block; radially projecting arms on said supporting block; a plurality of seat supporting arms, each pivotally connected at one end to one of said supporting arms on said block and adapted for projecting upwardly at an inclination to said block, one of said seat supporting arms being of less length than the others; a flexible seat forming member; a rigid brace fixedly mounted to and extending along one edge of said seat forming member and pivotally connected intermediate its ends to the free end of said short seat supporting arm; and means on said seat forming member for engaging the free ends of the other of said 45 seat supporting arms.

In testimony whereof I have signed the foregoing.

RALPH B. LONG.
